UNITED STATES PATENT OFFICE.

WILLIAM E. TAYLOR, OF EASTPORT, MAINE, ASSIGNOR TO AMERICAN CAN COMPANY, OF NEW YORK, N. Y., A CORPORATION OF NEW JERSEY.

SARDINE-CAN.

1,055,429.

Specification of Letters Patent. Patented Mar. 11, 1913.

Application filed October 27, 1910. Serial No. 589,445.

To all whom it may concern:

Be it known that I, WILLIAM E. TAYLOR, a citizen of the United States, residing in Eastport, in the county of Washington and 5 State of Maine, have invented a new and useful Improvement in Sardine Cans, of which the following is a specification.

My invention relates to improvements in sardine cans.

10 The object of my invention is to provide a sheet metal sardine can of a simple and efficient construction adapted to be rapidly and cheaply manufactured, to have the cover soldered on the body after the can is filled 15 without danger of producing leaks in the soldering operation, or of scorching or injuring the contents of the can, and which will also be adapted to be readily and conveniently opened.

20 My invention consists in the means employed to practically accomplish this object or result as herein shown and described, and more particularly specified in the claims.

In the accompanying drawing forming a 25 part of this specification, Figure 1 is a perspective view of a sheet metal can for sardines or other articles embodying my invention. Figs. 2, 3 and 4 are sections on lines 2-2, 3-3 and 4-4, respectively, of Fig. 1. 30 Fig. 5 is an enlarged detail section on line 5-5 of Fig. 1 and Fig. 6 is a detail plan view of the can body after the cover is applied, but before the body flange is folded. Fig. 7 shows a modification of the cover.

35 In the drawing, 1 represents the body of a sheet metal sardine can embodying my invention, the same being preferably of a one piece, seamless, drawn construction of generally rectangular shape, with rounded 40 corners 2 uniting its upright longitudinal and transverse sides 3, 4. The integral bottom 5 of the body is preferably upwardly paneled or countersunk, the marginal wall 6 of the countersink serving to materially 45 strengthen the body.

The can body 1 is provided at its upper end with a relatively wide outstanding or right angle seam flange 7, provided with a solder film or coating 8 on its upper surface, 50 fusibly united with the tin coat surface of the body flange. The purpose of this solder coating 8 is to enable the seam flange of the cover to be soldered or fusibly united to the corresponding seam flange 9 of the cover 10 55 by a simple fusing operation, or subjection

of the projecting seam flanges of the body and cover to the necessary heat to fuse this solder film or coating 8. The seam flange 9 of the cover 10 is a relatively narrow one and fits flat against and in snug metal to 60 metal contact with the solder coated seam flange 7 of the can body. And during the heating or fusing operation, the cover flange is held in snug, tight, close, metal to metal contact with the seam flange of the body by 65 folding the outer portion 11 of the body seam flange over the outer edge portion of the seam flange of the cover, the seam flange of the body being made wider than the seam flange of the cover to provide for this cover 70 clamping fold on the seam flange of the body, excepting at one of the rounded corners of the body where the seam flange of the body has a relatively narrow portion 12 to enable the integral projecting tongue 13 at 75 one of the rounded corners of the cover to be folded around and under this relatively narrow portion of the seam flange of the body.

The cover 10 is provided with a downwardly extending registering wall 14 adapted to fit snugly within the upper end or mouth portion of the can body to register the cover in position on the can body. This registering wall 14 may preferably be 80 formed by providing the cover with a downwardly projecting bead 15 instead of by countersinking the cover.

As the solder coated seam flange of the body is relatively wide and is folded over 90 and embraces the relatively narrow outstanding seam flange of the cover all around the can excepting at the one rounded corner thereof where the projecting tongue 13 of the cover is adapted to be folded around and 95 under and embrace the seam flange of the body, the cover is very firmly clamped and held on the can body at all points of the interengaging seam flanges, thus enabling a 100 hermetically tight solder joint to be formed with certainty and uniformity by simply subjecting the outstanding seam flanges of the body and cover to the necessary heat to fuse the interposed solder film. And as the 105 seam flanges of the cover and body are outstanding or outwardly projecting, the same may be readily subjected to the necessary heat to effect the fusing of the solder without danger of scorching or injuring the contents of the can.

To enable the can to be readily opened by rolling off the cover by means of a key, the cover is preferably provided with scores or weakened lines 16 extending, one from one edge of the tongue 13 diagonally across the cover inside the solder seam and the other from the other edge of the tongue.

In operation, after the can body has been filled, the cover is applied and then the relatively wide seam flange of the cover is folded around and over the relatively narrow seam flange of the cover, and the tongue of the cover is folded around and under the relatively narrow portion of the seam flange of the body. The outstanding or projecting seam flanges of the body and cover are then subjected to heat to fuse the solder film, the solder thus fusibly uniting both the upper and lower faces of the seam flange of the cover with the seam flange of the body.

In the modification of the cover shown in Fig. 7, the score or weakened line is located just inside the soldered seam.

I claim:—

1. The combination with a rectangular can body having rounded corners, and provided with an outstanding seam flange having a relatively wide portion extending all around the can body, excepting at one of the rounded corners thereof where said seam flange is relatively narrow, of a cover having an outstanding seam flange soldered to said seam flange of the body, said seam

flange of the body having a fold at the relatively wide portions thereof embracing said seam flange of the cover, said cover having at one of its corners an integral tongue extended over said relatively narrow portion of the seam flange of the body and adapted to be folded down and around the same at one corner of the body, substantially as specified.

2. The combination with a rectangular can body having rounded corners, and provided with an outstanding seam flange having a relatively wide portion extending all around the can body, excepting at one of the rounded corners thereof where said seam flange is relatively narrow, of a cover having an outstanding seam flange soldered to said seam flange of the body, said seam flange of the body having a fold at the relatively wide portions thereof embracing said seam flange of the cover, said cover having at one of its corners an integral tongue extended over said relatively narrow portion of the seam flange of the body and adapted to be folded down and around the same at one corner of the body, said cover having a marginal weakened line extending around the same over the side edges of said tongue, substantially as specified.

WILLIAM E. TAYLOR.
